Inventor:

Justus A. Traut,

By his Attorney,

F. A. Richards

UNITED STATES PATENT OFFICE.

JUSTUS A. TRAUT, OF NEW BRITAIN, CONNECTICUT.

SUSPENDER-BUCKLE.

SPECIFICATION forming part of Letters Patent No. 480,680, dated August 9, 1892.

Application filed April 4, 1892. Serial No. 427,599. (No model.)

To all whom it may concern:

Be it known that I, JUSTUS A. TRAUT, a citizen of the United States, residing at New Britain, in the county of Hartford and State of Connecticut, have invented certain new and useful Improvements in Suspender-Buckles, of which the following is a specification.

This invention relates to that class of suspender-buckles having box-and-slide cast-offs, the object being to provide a cast-off buckle having means for insuring proper operation of the cast-off when the slide is closed and having a slide constructed for permitting lateral movement thereon of the suspender-end. In the drawings accompanying and forming a part of this specification, Figure 1 is a front view of a box-and-slide buckle embodying my present improvements. Fig. 2 is a view of the back side of the buckle shown in Fig. 1. Fig. 3 is a vertical transverse section through the box and slide of the buckle in line *a a*, Fig. 1, showing the slide locked in place in the box of the buckle. Fig. 4 is a view similar to Fig. 1, but showing the slide closed for detaching the same from the box. Fig. 5 is a view of the back side of the buckle-slide and illustrates the operation of the pivotally-supported portion thereof.

Similar characters designate like parts in all the figures.

In Figs. 1 and 2 of the drawings the usual form of box B is shown forming the lower end of a buckle-lever L, whose upper end is pivoted in a well-known manner in the usual web-case or buckle-frame C. In Figs. 3, 4, and 5, inclusive, the web-case, not relating to my present improvements, is not shown.

The slide-box B consists of the front plate 2, the sides 3 and 5, and the back 4. The lower end of the front plate 2 is provided with the hook or catch 6, Figs. 3 and 4, for engaging in the slot of the slide-spring.

The buckle-slide consists of the back plate 8, which is folded at its upper end at 9 to form the slide-spring 10. This spring has formed therein the slot 12 for engaging the aforesaid catch of the slide-box. The lower end 10' of said spring projects to form a thumb-piece whereby to close the slide-spring from its position in Fig. 3 to its position in Fig. 4 for the purpose of detaching the slide from its box. The strap-carrying slide S at its lower end is

constructed or furnished with means for carrying the usual suspender-end (not herein shown) and is constructed to so engage the slide-box that on the closing of the slide-spring, as shown in Fig. 4, this is forcibly withdrawn from the catch 6, whereupon the slide may be freely withdrawn. For this purpose said slide S is shown provided with a suitable catch or lip, as 14, which when the slide is in place in the slide-box engages the slide-box in the manner shown to prevent any forward movement of the slide S in said box when the slide-spring is closed upon it.

As a means for supporting a strap-carrying loop, and also for providing the aforesaid slide-box-engaging catch or lip, the lower end of the slide S is shown folded over or formed into an eye or coil 13, in which said loop 15 is carried, as will be understood by comparison of Figs. 2 to 5, inclusive, the lip 14 being formed of the upwardly-extending middle portion of said folded-over end of the slide.

Another feature of my invention relates to the construction of the strap-carrying slide whereby the strap-carrying-loop is made movable sidewise of the buckle. For this purpose the slide S is formed of two parts *e* and *f*, which are pivotally connected at 16 by means of a suitable rivet or eyelet 17, whereby the lower part *f* is swiveled upon the upper one, so as to swing thereon, as indicated by solid and dotted lines, respectively, in Fig. 5. By this means a free sidewise movement of the strap-carrying loop 15 is obtained, which when the slide is in the buckle, as in Fig. 2, does not interfere with the proper operation of the catch or lip 14 for effecting the detachment of the slide from its box. In practice the user can detach the slide equally well whether said swiveled portion be in the position shown by solid lines in Fig. 5 or in the position thereof shown by dotted lines in said figure.

Having thus described my invention, I claim—

1. In a buckle of the class specified, the combination, with the box and its catch, of a strap-carrying slide consisting of two parts pivotally connected and having a spring constructed to engage the slide-box catch, substantially as set forth.

2. In a buckle of the class specified, the

combination, with the box and its catch, of a strap-carrying slide consisting of two parts pivotally connected, one of said parts having a spring constructed to engage the slide-box catch and the other part having a catch engaging the box for detaching the slide on the closing of the spring, substantially as set forth.

3. In a buckle of the class specified, the combination, with a slide-box substantially as described, of the buckle-slide consisting of the part *e*, having a box-engaging spring, and the part *f*, swiveled upon the part *e* and having a strap-carrying loop, substantially as set forth.

15 4. In a buckle of the class specified, the combination, with the slide-box, of the buckle-slide consisting of the two parts *e* and *f*, the one folded upon the other, the part *e* having the buckle-spring fixed thereto and construct-

ed to engage a catch on the slide-box and the other part having the strap-carrying loop supported in the folded lower end thereof and having the projecting lip for engaging the back plate of the slide-box, substantially as set forth.

5. The combination, with the box and with the catch on the front plate of the box, of the strap-carrying slide having a spring adapted to engage said catch and having on the strap-carrying end thereof the upturned lip constructed to engage the back plate of the box, whereby to withdraw the front plate from the catch on the closing of the spring, substantially as described.

25 JUSTUS A. TRAUT.
